UNITED STATES PATENT OFFICE

1,948,073

HYDRAULIC JACK

Robert E. Manley, York, Pa., assignor to The Manley Manufacturing Company, York, Pa., a corporation of Delaware

Original application January 5, 1926, Serial No. 79,435, now Patent No. 1,805,588, dated May 19, 1931. Divided and this application May 5, 1931. Serial No. 535,263

11 Claims. (Cl. 254—2)

This invention relates to automobile jacks, and has for its principal object the provision of a substantially fool-proof hydraulic jack having a high lift. 5 A further object of the present invention lies in the provision of a jack which can accommodate itself to a very small clearance, is simple to operate, and yet has sufficient capacity to raise a vehicle or other load to a satisfactory 10 height. Other objects of the invention will be apparent from the following description and claims.

Of all pieces of garage equipment it is believed the jack is most subject to abuse, and it 15 is therefore essential that an automobile jack be made as near fool-proof as possible, and particularly as regards to some means for preventing a thoughtless person from applying destructive power after the jack has been run 20 to its maximum height, or when the lifting portion of the jack has encountered a load beyond the possibilities of the jack.

With the present popularity of the balloon tires it has become quite necessary that a garage jack shall have a very low clearance and it is equally essential that the jack must be capable of taking a very heavy pleasure car to a rather greater height than required with high 25 pressure tires. It is also rather important that the jack should not be too heavy, but yet should be capable of lowering the larger cars with ease and dispatch, preferably without manipulating the lever which raises the car.

This application is a division of my application Ser. No. 79,435, filed January 5, 1926 which 30 became Patent No. 1,805,588, dated May 19, 1931.

In the drawings:

Figure 1 is a side elevation.

Figure 2 is a longitudinal cross section.

Figure 3 is a plan view.

Figure 4 is a transverse section on line 4—4 of Figure 3.

Figure 5 is a longitudinal cross section on line 5—5 of Figure 3.

Figure 6 is a plan view partly broken away of the connecting casting.

Figure 7 is a transverse view thru the axis of the saddle.

Figure 8 is a longitudinal section thru the 50 axis of the pump plunger.

Figure 9 is a transverse section thru the reservoir thru the inlet valve to the pump.

The main frame or chassis of the jack is built up of two upper bars 10 and two lower 55 bars 11 connected to one end at the front cast-

ing 12 and at the other end by the rear axle 15, which is secured in each of the rear brackets 16 by a set screw 17, the brackets 16 each being permanently fastened to both the upper and the lower bars 10 and 11, respectively, by 60 means of rivets such as 18. Supported by the side bars 10 and 11 on each side are two large castings 20 and 21, the former being for the tank and pump while the latter, the front casting 21, forms the cylinder in which the hydraulic piston or ram slides. The pump piston or plunger 22 is connected by a link 23 with a lever 24 pivoted to the shaft 25, the upper end of the lever forming an upright socket 27 to receive the tongue 28, which is fastened in the socket 70 27 by means of the usual binding bolt 29. The jack is moved from place to place by means of the transverse grip bar or handle 33.

The main piston or ram 32 carries a wrist pin 30 fastened by a set screw 31. This wrist pin 75 extends far beyond the piston and projects between the top and bottom side bars 10 and 11 where it is pivoted at each side to the walking beams 36 by means of links 38 each of which carries a lug 39 to which is secured a spring 60 40 attached at its free end to the frame, and tending to telescope the piston 32 into its cylinder 21.

The walking beams 36 are pivoted on the free ends of the upper shaft 40' which is mounted in 85 brackets 42 which may be integral with the casting 21. To these same brackets 42 at 53 are pivoted the drag links 44 having for their purpose the vertical positioning of the post 45, which carries at its top the usual saddle 46 to engage 90 a load to be lifted.

In order to secure rigidity of the walking beam structure it is found convenient to bolt the two beams 36 together by means of a rod 47 and a spacer pipe 48 held in center position between 95 49 and engaging the beams 36, as by the nuts 49. The post support or sleeve 50 has a pair of trunnions 51 to serve as pivots for the support 50 in the walking beams 36, and also has a pair of shorter trunnions 52 serving as a pivotal connection for the drag links 44 so that, since the pivots 40' and 53 are directly above one another, the pivots 51 and 52 will likewise remain one directly above the other in view of the parallel relation maintained by the bars, the vertical 100 distance between the two pivots of each pair being the same.

The upper portion of the tank casting 20 forms an oil reservoir 54 closed at the top by a cover 55 which should be moderately strong for 110

while there is normally no pressure in the oil chamber the oil from the ram cylinder is discharged back to the reservoir under a pressure dependent upon the weight of the vehicle which has been lifted. The corners of the reservoir chamber walls are filleted as at 56 to provide sufficient metal to receive the screws 57 and the walls are also thickened where necessary, as by the boss 58 for example, to support the various connections. The lower longitudinal rib 59 is merely for additional strength and is naturally optional.

The bottom of the tank casting 20 is formed by an integral member 60 in which there is a cylindrical bore 61 snugly receiving the pump piston or plunger 22, being in fact the cylinder thereof. A ball valve 62 held in place by the spring 63 admits oil thru the ports 64 and 65, during the suction stroke of the plunger, but closes communication between the main tank body or reservoir 54 and the plunger cylinder bore 61 during the powerstroke. As the handle 33 is moved downward and rearward the lever 24 and link 23 move the plunger 22 inward, driving oil thru the passage 66 in the casting 67 and past a check valve 68 to the horizontal passageway 69 and into the chamber 70 of the forward cylinder 21. The piston 32 is provided with a cup washer 72 substantially oil tight, so that as oil is driven into the chamber 70 the ram will move forwardly (i. e., toward the saddle 46) carrying with it the wrist pin 30 and consequently swinging the walking beams 36 about their pivots 40' so as to raise the saddle or load support 46.

A foot pedal 80 pivoted at 81 controls a rod 82 pivotally connected to the foot pedal 80 as at 83, which rod passes thru a bore 85 in the tank casting 20, and its free end terminates just short of a guide block 87 mounted in the rear wall to the tank casting 20, the block being held in proper position with respect to the check body 67, by the lock nuts 88 and 89. A spring 90 engages the front wall of the tank casting 20 and also a collar 92 threaded on the rod 82 so as to hold this rod yieldingly in contact with a rather short cylindrical needle valve 95, the conical point of which seats in a similarly tapered bore 96 in the guide piece 87 while the body of the needle valve slides freely in the cylindrical bore 97 at the front end 98 of the guide piece and is constantly in contact with the rod 82 except momentarily when the spring 90 is compressed by the foot pedal 80.

A nipple 100, preferably communicating with the stuffing box groove, connects the rear end of the piston chamber 70 to the tank chamber by means of a pipe 102 connected to the tank chamber by means of an ordinary union 104, and the nipple 105 threaded into the tank casting. This arrangement is to prevent loss of oil as I find it advantageous to provide some arrangement for while the three oil grooves 108 allow but a very slight leakage, there is always some leakage, with or without rings, and this leaked oil finds its way back to the tank by way of the pipe 102, there being no restriction to rearward flow in this pipe (there is no pressure in the tank) and the pressure behind the ram therefore drives the oil back to the tank since it is not possible to escape thru the stuffing box 109 closing the end of the pump cylinder in the usual manner.

The connecting casting or check body 67 is connected to the guide member 87 (which as

shown has a bore completely thru it) by means of a short straight pipe 110 threaded into the casting 67 as at 111, and threaded into the guide piece 87 as at 112, this means furnishing the return passage for the oil from the chamber 70. A load on the saddle 46 or the pull of the spring 40 or both tend to cause the piston 32 to move forwardly, in case the needle valve 95 is free to move, as when the pedal 80 is pushed rearwardly at the top, in which case the oil passes from the chamber 70 thru the passageway 69, the passageway 114 in the outstanding lug of the casting 67, thru the passage 115 in the pipe 110, into guide 87, and finally into the tank 54 thru the opening 117 in the guide piece 87.

Leakage thru the stuffing box 120 is prevented by providing an annular groove 121 in the forward end of the cylindrical chamber 60 and having this groove communicate with the tank 20 by means of a small vertical passage 123. There is no tendency for oil to flow into the groove 121 from the tank chamber as the plunger 22 is solid and its rear end never passes the groove. This leakage preventing means, and the quite similar means at the forward end of the ram cylinder are important features of the present invention as they insure against the untidiness almost invariably associated with hydraulic jacks of all types suitable for garage use.

It will be noted that the check body 67 is threaded into the tank casting 20 as at 130 and is also threaded into the forward or ram cylinder 21 as at 131, hence it is necessary to provide some manner of adjustably mounting the guide block 87 with respect to the check body 67. The check body is tapped as at 111 to receive one end of the pipe 110 and the guide block 87 is also tapped at 112 to receive the other end of this short pipe in order to assemble the device, consequently the guide block 87 must be free to move with respect to the tank casting. I therefore make the threaded rear portion of the guide member 87 smaller than the hole 133 in the boss 58 of the tank casting which receives it so as to provide a loose fit. When the other parts of the device are properly assembled and in permanent position the two lock nuts are brought to bear against opposite sides of the boss 58 in the tank casting so as to make an absolutely oil tight joint, packing 135 being provided in the usual manner. The small longitudinal rib 136 is optional but it is very convenient to strengthen this small block, particularly in view of the vertical discharge orifice 117.

The operation of the device is as follows:— The jack as a whole is pulled from place to place by means of the tongue 28 which is prevented from moving rearwardly, that is, in a direction toward the load support, by a stop member 137 bolted on the link 23 in such position as to engage the pipe spacer 138 so as to insure that the plunger or solid piston 22 shall never be withdrawn from its cylinder. In such position the jack may conveniently be pushed forward into position under the car to be raised. If it is necessary to shift the rear wheels sideways this can readily be accomplished by lowering the handle 33 until the end of the plunger engages the threaded end 130 of the check body 67. With the parts in such position a slight further lowering of the handle 33 permits the forward end of the jack to be swung about the front ground wheels 140 as a pivot, raising the much larger ground wheels 141 slightly off the ground. When desired the saddle 46 may be

raised with respect to its threaded sleeve 50 by revolving it in the usual and well known manner within the limit of length of its post 45.

6 When in exactly the position desired, the handle 33 is reciprocated, on the upward stroke drawing oil from the reservoir 54 thru the vertical passage 64 and past the ball 62 which readily yields downward against the spring 63 80 so as to allow the oil to pass thru the horizontal transverse opening 65 leading to the pump cylinder 61. On the downward stroke of the handle 33 and post or tongue 28 the solid piston or plunger 22 moves rearwardly, that is, 10 toward the load, until a convenient lowest position is reached or in case of a long stroke until the cup washer 150 strikes the tapered threaded rear end of the check body 67.

The oil behind the ram 32 forces the latter 20 toward the rear axle 15 and this movement swings the walking beams 36 about their pivoting shaft 40 by means of the transverse wrist pin 30 at the rear end of the ram and the two 25 parallel links 38 which are pivoted to the walking beams at the lower ends of their short power arms while the load itself is carried at the free end of the longer load carrying arms of the walking beams which load carrying arms are horizontal when they have moved roughly one 30 third of their upward travel. The two walking beams with their rigid cross connections 47-48-49 form a load carrying frame.

Should the ram or the load support meet an 35 obstacle beyond the strength of the jack no harm is done for the spring 90 is set to open the needle valve 95 at a pressure giving a satisfactory factor of safety over the possible capacity of the jack. Hence excessive pressure within the chamber 70 simply causes the valve 40 95 to move away from the seat 96 thus allowing the discharging of oil thru the opening 117 until the pressure is reduced to the selected maximum pressure, the return being via the horizontal bore 69, the short vertical passage 45 155, the transverse passage 114 from the passage 155 to the pipe 110, passage 115 in the guide block 87 and into the reservoir 54 thru the opening 117.

I find it desirable to make the capacity of the 50 reservoir 54 just sufficient to carry the load to the highest position desired, that is, the cubic capacity of the reservoir shall exactly balance the cubic capacity of the chamber 70 at maximum movement of the ram plus the capacities of the various passageways.

In case it is preferred that the reservoir shall 55 be able to hold an excess or reserve supply of oil some other means for limiting the stroke of the ram must be provided so I have shown a positive stop at 158 which is engaged by the wrist pin 30 at each side and thereby limits the movement of the ram on its working stroke.

To lower the load, the mechanic presses his 60 foot against the upstanding lever 80 at the front of the truck and this withdraws the rod 82, compressing the spring 90 and allowing oil to pass from the ram cylinder 70 back to the reservoir 54 exactly as just described in connection with excess pressures. It should be noted that the operator can lower the load 65 either very slightly or very slowly by pressing the foot treadle or lever 80 just sufficient to allow a slight escape of oil. The valve 95 is of such length as to remain within its guiding bore 97 when the rod 82 is withdrawn to its

greatest extent. The return passages are of such size with respect to the volume of oil used that while the lowering of the load may take place in a very short period the action is always smooth even tho the pedal 80 is held to maximum release position.

What I claim is:

1. In a jack having a chassis, a pair of spaced parallel levers pivoted about alined axes in said chassis, spaced means for joining said levers to form a frame, a load support on one of said means, and means beneath said alined axes and on said chassis for rocking the frame to raise and lower the load support. 80

2. In a jack having a chassis, a pair of spaced parallel levers on opposite sides of said chassis pivoted about alined axes in said chassis, spaced means for joining said levers to form a frame, a load support adjustably mounted on one of said means, and means beneath said alined axes and on said chassis for rocking the frame to raise and lower the load support. 90

3. In a jack, a pair of walking beams, a member pivoted to both walking beams, a load support carried by said member, a ram, and a pair 100 of links connecting said ram and the ends of the walking beams distant from the load support.

4. In a jack, a ram cylinder, a shaft directly above and transverse of said cylinder, a pair of 105 levers pivoted on said shaft, each having a horizontal load carrying arm and a downwardly extending power arm, a ram, and a link connecting each power arm with said ram.

5. In a jack, a wheeled truck, a bell crank 110 lever having a forwardly extending load carrying arm and a power arm, pivoted on said truck on a transverse horizontal axis, a member reciprocatingly mounted in said truck, and a link connecting the forward end of said member with 115 said power arm.

6. In a jack, a wheeled truck, a ram cylinder carried thereby, a ram in said cylinder, a load carrying arm pivotally mounted on said truck about an axis at a higher level than the center 120 line of the ram, and means connecting the ram to the said arm.

7. In a jack, a wheeled truck, a pump and a ram carried in tandem fashion on said truck, a load carrying arm pivoted about a transverse 125 axis so that its load carrying end is at one end of the truck in lowered position, a handle for transporting the truck and for operating the pump, linkage connecting the ram and arm, and means secured to the truck adjacent the pump 130 for limiting movement of the pump in one direction.

8. In a hydraulic jack having a ram, a ram cylinder, a pump, and a reservoir so connected that the pump draws fluid from the reservoir 135 and forces it into said ram cylinder behind said ram, a transverse shaft directly above the ram cylinder, a bell crank lever pivoted on said shaft with its one arm extending downwardly to one side of the ram cylinder, and a link connecting 140 the ram with said downwardly extending arm.

9. In a hydraulic jack having a ram, a ram cylinder, a pump, and a reservoir so connected that the pump draws fluid from the reservoir and forces it into said ram cylinder behind said 145 ram, a lug extending laterally from each side of the ram, a shaft parallel to said lugs, a pair of load carrying levers pivoted on said shaft and each having a power arm, and links connecting said arms with said lugs. 150

10. In a jack, a long narrow wheeled truck, a tank casting and a ram cylinder mounted in tandem fashion thereon, a pair of brackets rising from the ram cylinder, a load carrying arm mounted in each bracket, means connecting the two arms to form a load carrying frame, a saddle carried by said frame, and means connecting said ram and said frame to raise and lower said saddle.
11. In a jack, a long narrow wheeled truck, a

tank casting and a ram cylinder mounted in tandem fashion thereon, a pair of brackets rising from the ram cylinder, a load carrying arm mounted in each bracket, means connecting the two arms to form a load carrying frame, a saddle carried by said frame, means connecting said ram and said frame to raise and lower said saddle, and means for keeping the saddle axis perpendicular to the axis of the ram. 80
